UNITED STATES PATENT OFFICE.

JAMES F. FERRY, OF DELTA, COLORADO.

HYDRANT.

987,290.

Specification of Letters Patent. Patented Mar. 21, 1911.

Application filed July 7, 1910. Serial No. 570,797.

To all whom it may concern:

Be it known that I, JAMES F. FERRY, residing at Delta, in the county of Delta and State of Colorado, have invented certain new and useful Improvements in Hydrants, 5 of which the following is a specification.

My invention relates to water hydrants, and it particularly has for its object to provide a hydrant of a simple and effective 10 construction wherein means are provided for preventing water waste from going into the ground when the hydrant valve is shut off and to deliver the water that would otherwise drip from the outlet spout through 15 such spout after the hydrant valve is cut off as a part of the regular stream.

The invention also has for its object to provide a hydrant in which waste water or surface drainage will not get into the hydrant to contaminate the water therein, and 20 the invention also has for its object to provide a hydrant in which freezing of the water will be prevented.

Generically the invention comprises a 25 main rotary valve preferably of the type disclosed in my Patent #936,877 of October 12, 1909, to the casing of which valve an inner casing is jointed and to which valve casing a reducing joint is secured 30 which connects with the source of water supply. The inner casing incloses a water pipe which interlocks with the rotary valve which when turned causes the rotary valve to open or close, the water pipe being spaced 35 from the walls of the inner casing and projected through the top thereof where it carries an outlet spout or faucet. Within the water pipe is another pipe that extends down to near the rotary valve and has its 40 upper end projected through the top of the water pipe and joined to an air reservoir or compression chamber. An outer casing is threaded into the reducing joint and incloses the inner casing so that the inner 45 casing, the valve and its contained parts may be removed for repairs if necessary.

More specifically the invention resides in those novel details of construction, combination and arrangement of parts, all of 50 which will be first fully described, then be specifically pointed out in the appended claims, and illustrated in the accompanying drawings, in which:

Figure 1, is a sectional perspective view 55 illustrating the application of my invention, the rotary valve being open. Fig. 2, is an

enlarged, central, vertical, longitudinal section of the invention, parts being broken away and showing the rotary valve closed. Fig. 3, is an enlarged section of the rotary 60 valve mechanism showing the position of the parts when such valve is open. Figs. 4 and 5 are sections on the lines 4-4 and 5-5 on Figs. 3 and 2, respectively. Fig. 6, is a sectional perspective view of a modified form of the invention, the rotary valve being open. Fig. 7, is an enlarged central 65 vertical section of the form shown in Fig. 6, parts being broken away and showing the rotary valve closed. Figs. 8 and 9 are respectively sections on the lines 8-8 and 9-9 of Figs. 6 and 7. Fig. 10, is an enlarged section of the rotary valve mechanism showing the position of the parts when 70 such valve is open.

Referring now to the accompanying drawings in which like letters and numerals indicate like parts in all of the figures, 13 designates the rotary valve whose casing 10^x is externally threaded at 10^a to receive 80 the union 2^x, the union 2^x screwing onto the tapped end 1^a of the inner casing 1. The other end of the casing 1 is closed by a cap 3 in any approved manner. Threaded onto the valve casing 10^x below the union 2^x is a 85 reducing joint 4^x whose reduced end 5^x joins with the supply main 6.

7 designates the water pipe which projects through the cap 3 and has its upper end secured at 8 to the air reservoir 9. The 90 air reservoir is connected with a pipe 9^a that projects down into the water pipe 7 and is spaced therefrom and terminates adjacent to the valve casing 10^x. The pipe 7 has an outlet 7^a to which a faucet 7^b (see 95 Fig. 1) or a simple spout 7^c (see Fig. 7) may be attached. The pipe 7 has a collar 7^d within the casing 1 near its top to take off the wear on the cap.

The valve mechanism may be of essentially the same construction as disclosed in my patent hereinbefore referred to as heretofore stated, and in its generic nature comprises the casing 10^x which has a reduced lower end 10^d on which the cap plate 11 is threaded, the cap plate 11 having apertures 11^a to register with the apertures 12^a in the web 13^a of the rotary valve 13. The pipe 7 has its lower end reduced as at 7^e to snugly fit within the valve 13 and it is 105 provided with lugs 7^f that enter the longitudinal slots 13^b of the valve 13. The pipe 110

7 is also provided with radial lugs 7^e that enter the bayonet slots 10^e of the valve casting 10^x so that when the rotary valve is open, as shown in Figs. 1 and 3, of the drawings, the pipe 7 will be interlocked with the valve casing 10^x through the medium of the lugs 7^e and bayonet slots 10^e and when the valve is closed, as shown in Fig. 2, the pipe 7 may be withdrawn therefrom in a manner similar to the withdrawal of the corresponding member in my patent hereinbefore referred to.

In the practical operation of my invention when a faucet 7^b is used, the rotary valve 15 may be left open, as shown in Fig. 1 of the drawings, and the water turned on or off through the faucet 7^b. When, however, a simple spout 7^c is used, as shown in Fig. 7 of the drawings, the water is turned on or off 20 by rotating the pipe 7, thereby opening or closing the rotary valve in a manner readily understood by those skilled in the art.

When the rotary valve is open and water is flowing through the outlet spout 7^c or 25 faucet 7^b, the air within the chamber 9 and pipe 9^a will be compressed so that as soon as the rotary valve is closed this compressed air will force the water out of the spout 7^c or open faucet 7^b to a sufficient degree to 30 prevent dripping of the water at the outlet spout, but should the water within the hydrant get chilled below the freezing point and expand, it will back up into the pipe 9^a and bursting of the pipes will be avoided.

35 In order that the valve mechanism may be readily removed for repairs or cleaning if necessary, I inclose the inner casing 1 and the valve casing 10^x in an outer casing 100 whose lower end threads into a counter-bore 4^y of the reducing joint 4^x and whose upper end is flanged at 100^a to be secured to the flange 1^y of the casing 1 by the screws 1^z that screw the cap 3 in place. When it is desired to remove the valve mechanism it 40 is only necessary to remove the screws 1^z and turn the casing 1 to unscrew the valve casing 10^x from the web 4^z of the reducing joint 4^x when the entire structure within the casing 100 may be removed. The casing 100 further serves as a wall to prevent the 45 earth and moisture entering the hydrant.

In the modified form shown in Fig. 6 *et seq.* the construction is substantially the same as in the other form except that the 50 outer casing 100 is omitted and the reducing joint 4^x has but one bore at its larger end to receive the casing of the valve 10 which in the form referred to has a flange 10^b by means of which the member 2 the valve is secured in the casing 1. The water from the main pipe enters the joint 4^x at 5, as in the other form of the invention.

60 From the foregoing description taken in connection with the accompanying draw-

ings, it is thought the complete construction, operation and advantages of my invention will be readily understood by those skilled in the art to which the invention appertains.

What I claim is:

1. A hydrant comprising a casing, a rotary valve mechanism carried by said casing and including a rotary valve member, a source of water supply joined with said rotary valve mechanism, a water off-take pipe interlocked with said rotary valve mechanism whereby when said pipe is turned said valve will be opened or closed according as said pipe is turned one way or the other, an outlet to said pipe and an air compression chamber in communication with said pipe adjacent to said rotary valve.

15 2. In a hydrant, a casing, a rotary valve carried thereby, a source of water supply 85 connected with said casing to deliver through said valve, a water off-take pipe projected into said casing and spaced from the walls of the same, means for interlocking said pipe with said rotary valve in virtue of which said rotary valve will be 90 opened and closed according as said water offtake pipe is turned one way or the other, a valved outlet for said water pipe, an air reservoir carried by said water pipe, a pipe 95 connected with said air reservoir and projected into said water offtake pipe and communicating therewith at the bottom.

3. In a hydrant, a source of water supply, a rotary valve mechanism including a valve 100 casing and a rotary valve within the same, said valve casing being connected to said source of water supply, a water off-take pipe having one end removably interlocked with said rotary valve in virtue of which 105 said valve may be opened or closed according as said pipe is turned one way or the other, an outlet for said water pipe near its other end, and a closed ended air duct projected within said water pipe and in 110 communication therewith near its lower end.

4. In a hydrant, a source of water supply, a rotary valve mechanism including a valve 115 casing and a rotary valve within the same, said valve casing being connected to said source of water supply, a water off-take pipe having one end removably interlocked with said rotary valve in virtue of which said valve may be opened or closed according as said pipe is turned one way or the other, an outlet for said water pipe near its other end, an air duct projected within 120 said water pipe and having one end in communication therewith near its lower end, and an air reservoir carried by said duct above said water off-take pipe in communication with the other end of said duct.

5. In a hydrant comprising a casing, a rotary valve mechanism carried by said cas-

- ing and including a rotary valve member, a source of water supply, a joint connecting said source of supply with said casing, a water off-take pipe interlocked with said 5 rotary valve member whereby when said pipe is turned said valve member will be opened and closed according as said pipe is in one position or the other, an outlet to said pipe, an air compression chamber in 10 communication with said pipe adjacent to said rotary valve, another casing inclosing said first mentioned casing, said other casing having its lower end secured to said joint. 15 6. In a hydrant, a source of water supply, a rotary valve mechanism including a valve casing and a rotary valve within the same, a joint connected to said source of supply and to said valve casing, said valve mechanism controlling passage of water through 20
